UNITED STATES PATENT OFFICE.

FRANZ LOUIS WÄCHTLER, OF GROSSENHAIN, GERMANY.

TOOL-GRINDING MACHINE.

Application filed October 16, 1919. Serial No. 331,213.

To all whom it may concern:

Be it known that I, FRANZ LOUIS WÄCHTLER, a citizen of the Republic of Saxony, Germany, residing at Grossenhain, Germany, have invented certain new and useful Improvements in Tool-Grinding Machines (for which I have filed applications in Germany, G. 46,302 XII/67^a, dated 21st of February, 1918; Germany, G. 46,536 XII/67^a, 5 dated 13th of April, 1918; Germany, G. 46,953 XII/67^a, dated 26th of July, 1918; Germany, G. 47,599 XII/67^a, dated 13th of January, 1919; Germany, G. 48,207 XII/67^a, dated 30th of April, 1919; Germany, 10 Gebräuchsmuster 686,802, dated 26th of July, 1918; Austria, dated 18th of January, 1919; Austria, dated 24th of June, 1919), 15 of which the following is a specification.

The heretofore known machines and apparatus for grinding tools, on which the mandrel carrying the tool is fitted between two center points, the headstocks of which are disposed on a reciprocating slide, so that the tool is passed before a stationarily journaled revolving grinding disc, still show— 20 even if working automatically—many drawbacks, which result in the teeth to be ground being attacked very unevenly by the grinding disc, so that the height of the ground teeth varies and the latter do not attack the work evenly; the consequence is that the projecting teeth easily break off, and the tool at least is soon blunted and becomes useless. Under an inaccurately regulated 25 pressure the cutting edges of the tools are frequently also heated so that they become soft and unserviceable because the reciprocated tool can be ground only while the tooth is passing the grinding wheel in one direction, as the dead point in the feed gear 30 renders it impossible to press the tool against the grinding wheel while the tooth is passing the latter in the opposite direction. Therefore automatic tool grinding 35 machine work uneconomically, even if the return of the tool is accelerated.

All these drawbacks are obviated by the new tool grinding machine according to the present invention; besides further advantages are derived, which shall hereinafter be disclosed by the description of the construction of the machine itself.

A feature of the machine according to the present invention consists therein that the

spindle of the center point supporting the one end of the mandrel is journaled so as to revolve freely, whilst it is held in a certain position (grinding position) by means action frictionally on it, which means are adapted to cause, by a corresponding control, a revolution of said spindle in the one direction; the said means, furthermore, will admit of a revolution of the spindle in the opposite direction when a force, greater than the grinding pressure acts on the spindle; so that the mandrel will on the one hand be held during its reciprocation in its grinding position by means frictionally acting on the center point spindle, and may, furthermore, be turned by the same during the operation when tools with helical teeth are being ground, whilst on the other hand the turning of the tool with reference to the pitch of its teeth may be performed during the grinding operation and without said frictional means being disengaged, as soon as the tool has moved out of the range of the grinding wheel.

It is further necessary that the gear parts which produce said turning of the tool engage only at the very moment necessary for the reversing, and are immediately after again disengaged, so as to allow the mandrel to revolve freely, independent of all gear parts employed for said turning. As everywhere in mechanical construction the most simple design will also here lead to securing a perfect working of the turning gear; therefore the known device of a ratchet wheel and pawls has been employed, said ratchet wheel having a number of notches for the engagement of the pawls, said notches corresponding in number with the number of teeth on the tool to be ground, so that by simply exchanging the ratchet wheel the turning or dividing gear as we may call it, may be readily adapted for tools of any number of teeth. The intention to secure the most simple design has furthermore lead to securing the said ratchet wheel immediately on the mandrel. This necessitated that the engagement of the pawl with the ratchet wheel cease immediately after the desired turn has taken place. According to the present invention this is obtained by the pawl being carried by a spur wheel freely revoluble on the mandrel. This spur wheel meshes with a wheel on a shaft par-

allel to the mandril, which shaft is oscillated after each operative stroke has been completed. The pawl has behind its fulcrum an extension, with which it engages in a recess in a controlling member, which is frictionally journalled in the mandril headstock. When revolved in one sense the said extension abuts against the one side of said recess, and thereby the pawl is brought into engagement with the ratchet wheel. When revolved in the opposite sense the said pawl extension will abut against the other side of the recess and thereby the pawl is lifted from the ratchet wheel. By such simple means it is possible to hold the pawl in engagement with the ratchet wheel fitted directly on the mandril during the time only, which it is necessary for the respective turning, whilst during the other time, that is during the operative stroke, the mandril can revolve fully freely. By the ratchet wheel being fitted directly on the mandril, all troubles by intermediate gears are obviated, which, as experience has proved, cause an inaccurate adjusting or setting of the tool.

Once thus provision has been made that the setting of the tool relatively to the grinding disc may be performed independently of the dividing gear, also provision must be made for a proper operation of the machine, and also that the grinding wheel itself is reliably held in its position during the whole operation. In grinding machines, however, in which the shaft carrying the grinding tool or wheel runs at a high speed, it has been found that the said shaft readily heats considerably in its bearings. This leads to an elongation of the shaft, which will thereafter axially vibrate. This again will have the result that the position of the grinding wheel varies, so that the tool is submitted to an inaccurate grinding, more being ground off at some parts, less at others. This evil cannot be obviated by readjusting the heated shaft, because such readjusted shaft would seize on cooling down subsequently.

It is the object of the present invention to obviate also such drawbacks by arranging the shaft in such a manner that it is possible to compensate the change in the length of the shaft carrying the grinding wheel in such a manner that the said grinding wheel will always remain in exactly the same place and the shaft does not vibrate axially in its bearings.

In the accompanying drawings Figures 1 and 2 show the grinding machine in elevation, Fig. 1 being a side elevation and Fig. 2 an end elevation, seen in the direction of the arrow in Fig. 1. Fig. 3 is a vertical longitudinal section through the mandril with the respective driving gear. Fig. 4 is an end elevation seen in the direction of the arrow in Fig. 3. Fig. 5 is an approximately

horizontal section on the line 5—5 in Fig. 4. Fig. 6 is an elevation of the mandril headstock; Figs. 7 and 8 are vertical central sections thereof, in the one the chain wound around the spindle or its sleeve, respectively, having been omitted; Fig. 9 is an elevation of the mandril head stock seen from the rear; Fig. 10 is a detail side elevation partly in section of the mandril head stock; Figs. 11 and 12 show the dog and the grinding wheel. Figs. 13—17 refer to a modified construction of the brake device; Fig. 13 being again an elevation of the mandril headstock, Fig. 14 a vertical central section therethrough, and Fig. 15 an elevation of the mandril headstock seen from the rear; Fig. 16 is a special modification of the means of securing the chain; Fig. 17 is a top view of the chain stretched out. Fig. 18 is a longitudinal section showing the journaling of the grinding wheel spindle. Figs. 19 and 20 show the bearing of the grinding wheel shaft in two different positions, both seen from above.

From the driving shaft 1 (Figs. 1 and 2) the shaft 2, axially shiftable in its lower bearing, is driven by means of worm and worm wheel; the upper end of this shaft 2 is journalled in an overhang bearing of the body part 4, which may be raised and lowered by means of handwheel 5 and screw spindle 6. At the upper end of the vertical shaft is disposed a crank with connecting rod 7, which acts on a slide 9 guided on the slide table 8 and reciprocates the said slide. On said slide is fitted the headstock 10 and the mandril headstock 12. Between the center point of the mandril headstock and the center point of the headstock 10 is fitted the mandril 12 carrying the tool 11. By such means the tool is carried past the revolving grinding wheel 13, the shaft of which is supported in the forked bearing 14, when the slide 9 is reciprocated.

Close to the upper end of the vertical shaft 2 is fitted a cam disc, on the surface of which is disposed a roller 15, carried by lever 16 keyed to a horizontal shaft 17. In consequence thereof this horizontal shaft will be oscillated by the lever 16 as the roller overrides the projection on the cam disk at each revolution of the vertical shaft 2—viz, each time after the reciprocation of slide 9 on table 8 has been completed. This oscillation of shaft 17 is transmitted by rod gear to a horizontal shaft 19 disposed parallel to the mandril spindle 18 (see also Fig. 5). From shaft 19 the oscillation is transmitted by means of a spur gear train 20, 21 to the mandril spindle 18; it shall hereinafter be still described by what means hereby the oscillation will during such transmission act in one sense only on the said mandril spindle. By such means after each operative stroke, i. e., after each complete reciprocation of the tool,

the latter is advanced by one tooth, so that a fresh tooth will come into contact with the grinding wheel.

The mandril spindle 18 (Figs. 3 and 5) has fitted into its one end the center point 22 and to its other end a ratchet wheel 23, which is rigidly secured thereto by means of a nut 24 and a washer 25. The spindle runs in two ball bearings, disposed in the parts 10 26 and 27 of the forked headstock 12. The ball races 28 on the spindle 18 are held by means of an intermediate sleeve 29 and nuts 30 and 31. The ball races 32 in the bearings 26 and 27 are secured by means of a nut 33. 15 On an extension of the boss of part 26 is fitted freely revoluble a spur gear 21, on which a ring 34 is screwed. This ring 34 has a pin 35 on which is fitted a pawl 36, which cooperates with the ratchet wheel 23 20 in a manner to be hereinafter described. On the inner side of the extension of boss 26 an annular body is frictionally coupled thereto by means of a slip spring 37; said annular body having an upwardly extending horn 25 38 (Fig. 4). This horn has at its upper end a recess 39, in which engages a nose 40 on the boss of pawl 36.

The gear 21 carrying the pawl meshes, as before said, with the gear 20 on shaft 19. 30 This shaft 19, which is parallel to the mandril spindle is oscillated in the following manner: From the vertical shaft 2 the horizontal shaft 17, to which lever 16 is fitted, is oscillated once at each operative stroke by 35 means of the cam disc and the lever 16 engaging with roller 15 in the groove of said cam disc. To the one end of shaft 16 is fitted a lever 41, having in its free end a curved guide slot. In this guide slot a block fitted 40 to the end of a rod 42 may be adjusted. The said rod 42 acts on a lever 43 which is fitted freely revoluble on shaft 19 (Fig. 5). On the boss of this lever is fitted a spur gear 44 which meshes with another spur gear 45 45 revolvably fitted to a pin 46, and having fitted to its boss another spur gear 47. This spur gear 47 meshes with a spur gear 48 fitted to shaft 19. In consequence of this arrangement a stroke of lever 43 is transmitted by 50 gears 44, 45 and 47, 48 to shaft 19. The gear train has been employed in order to allow of readjusting the tool relatively to the grinding wheel. Such readjustment may be necessary in consequence of the wear of 55 the grinding wheel and the tool in course of time. For this purpose the pin 46, carrying the gears 45 and 47, is fitted to a worm wheel 49, the worm 50 of which may be turned by means of a hand wheel 51. The 60 turning of the worm wheel will cause the gears 45 and 47 to roll on the respective gears 44 and 48 and to thus cause a lead or lagging of the shaft 19, which means a fine adjustment of the total relatively to the 65 grinding wheel. The gear 20 fitted to shaft

19 is axially adjustable with its bearing carried by slide 9, for which purpose a key 52 of suitable length has been employed to hold gear 20 to shaft 19.

The mandril 12 with the tool 11 is held in operative position in the following manner: On the sleeve 29 fitted to the mandril spindle 18 is wound a chain (Fig. 8). The one end of this chain is run over a roller 53 and carries a weight 54. The other end of the chain is coupled to a slide 55. This slide travels in guides 56 crosswise to the axis of the mandril spindle, the said guides being fitted to the headstock 111. In the middle of the guides 56 is disposed a pin 57, on which a pawl 58 is pivoted. This pawl can be thrown over so that it engages in a recess 59 in slide 55 (see dotted lines in Fig. 8). When the said pawl thus engages in the recess in slide 55, the latter will be held in a given position, the pull of the weight 54 on the chain forcing the slide against the pawl. As now, owing to the weight, the chain wound around sleeve 29 has a high friction on the latter, the mandril spindle, which is freely revoluble in its bearings 26 and 27 is held in its position determined by the position of the slide. The friction of the chain is so great, that it exceeds the grinding pressure. It is only necessary to provide that this position of the sleeve 29, and therefore also on the mandril spindle 18 corresponds to the operative position, i. e., that position in which the tool bears with the face of one of its teeth against the grinding wheel 13. The fine adjustment is performed by aid of handwheel 51 in the manner hereinbefore described.

When, now, a fresh tooth of the tool is to be brought into contact with the grinding wheel, the tool will have to be advanced, and this will have to be at the moment when the tool has been moved out of the range of the grinding wheel, i. e., after it, during its reciprocating stroke, has been passed twice along the grinding wheel. This advance is performed in the following manner: The gear 21 carrying the pawl 36 meshes in the manner hereinbefore described with gear 20 on shaft 19. Shaft 19 is oscillated, therefore also gear 21, carrying pin 35 of the pawl. Therefore also the extension 40 is oscillated. If now the oscillation proceeds in the direction of the arrow in Fig. 4, the extension will bear against the left side of the recess 39. Thereby the pawl 36 is pressed into the ratchet wheel 23. It engages in the next notch therein and thus produces the movement necessary for turning the mandril spindle 18. At the immediately following return the extension 40 bears as shown in the drawing, against the other side of the recess 39 and thereby the pawl is lifted out from the ratchet wheel. At a further turn in this direction the shoulder 60 of extension 130

40 finally bears against the upper end of the part 38 having the recess 39, so that said part 38 is dogged against the action of its brake spring.

- 5 During the interval between each two advances of the mandril spindle 18 and therewith also of the tool 11 on the mandril 12 tools with helical teeth must undergo a twist of the mandril 18 corresponding to the helical twist of the teeth. This twist may be performed by the parts producing the advance without affecting the mandril spindle, because the pawl is lifted out immediately after the advance has been completed. The 15 arrangement which produces the twist of the mandril spindle in correspondence with the helical twist of the tool must be so constructed that it allows of the spindle being twisted during the advance. The mandril spindle is 20 twisted in correspondence with the helical twist of the tool teeth is performed by aid of the hereinbefore described slide 55. This slide has at its lower end a roller 61, with which it engages on a guide bar 62, when 25 the pawl 58 is lifted. This guide bar swivels on a central pin 63 and may be fixed in any adjusted position. The guide bar is stationary and therefore does not participate in the reciprocating movement of slide 9 on table 30 8. On the other hand the slide 55 gliding crosswise to the axis of the mandril spindle is dogged together with its guides 56 during the reciprocating movement of the tool. In follows therefrom that the slide will during 35 such reciprocating be lifted and lowered by the slantingly disposed guide bar 62. The adjustment of the guide bar must correspond to the twist of the teeth of the tool. The slide 55 is held with its roller 61 down on 40 the guide bar 62 by means of the weighted chain. The pull of this weight has the effect that the chain wound on the sleeve 29 exerts a pull on the slide 55, on the one hand, and on the other that on the slide 55 being raised 45 and lowered, by the friction of the said chain the sleeve 29, and with it the mandril spindle 18 is dogged.

According to the present invention the chain is constructed in such a manner that 50 its upper part acting on the slide 55 is composed of two parallel thrums 64, whilst the lower, weighted part consists of one thrum 65 only, in such a manner that the part 65 remains in the gap between the two thrums 64, where the chain is wound on the sleeve 29. Thereby it is possible that the middle line of the chain always remains in the same plane although the chain is wound on the sleeve 29. When now a force appears which 55 tends to turn the sleeve in the direction of the pull of weight 54, viz., contrary to the arrow shown in Fig. 8 within the sleeve 29, the friction of the chain on sleeve 29 will oppose such force. Such force is the grinding 60 pressure exerted by the grinding wheel on

the tool. When, on the other hand, a force appears, which tends to turn the sleeve 29 and the mandril spindle 18 in opposite direction—viz., in the direction of the arrow shown in Fig. 8 inside of the sleeve 29—such 70 turning may proceed without any difficulty, as the weight acts towards slackening the chain. Such turning will proceed when the advance is being made, as in this case the mandril spindle 18 is by the ratchet gear 23, 36 dogged in the direction of the arrow (Figs. 4 and 8). The advance will therefore 75 not affect the weighting parts, which produce the twisting of the mandril spindle 18 during the operative stroke of tools with 80 helical teeth. On the contrary these parts are so formed that they will even assist the twisting of the spindle for advancing the tool.

It must be remembered that the rough 85 adjustment of the tool may be performed without the parts serving for the fine adjustment of the mandril, in particular the worm 50 being operated by the hand wheel 51 as this would require too much time. For obtaining this rough adjustment the dog, which couples the mandril with the mandril spindle, is made of a special form. This dog consists of a part 66 screwed to the end 90 of the mandril. On a screw bolt 67 (see 95 Fig. 11) are fitted two jaws 68, one to the right and one to the left of the part 66 screwed to the mandril. These jaws form a fork. They engage in a circular groove 69 in the nut 31 on spindle 18 and are of a corresponding curvature. When, now, one of the nuts 70 on the end of bolt 67 is tightened, the jaws 68 are clamped both to the dog 66 and into the annular groove 69. By such means the mandril 12 is dogged. As 100 soon as one of the nuts is loosened, the clamping pressure ceases which holds the jaws 68 in the annular groove 69. Then the dog may be turned at will with the mandril 12. This possibility of turning the mandril 110 is employed for rough adjusting the tool. If one of the nuts 70 is loosened, and the center point is withdrawn into the headstock 10 by turning handwheel 71, the mandril 12 may be taken with the tool from the machine. 115

In Fig. 12 the grinding wheel 13 is shown in contact with the tool 11. One may see how the tooth being ground bears with its face against the grinding surface. The arrow indicates the direction opposite to that in which the mandril must be advanced for the next tooth to be brought into contact with the grinding wheel.

As hereinbefore described the adjustable 120 guide bar 62 on which the slide 55 rides with its roller 61 serves to give the mandril spindle a twist corresponding to tools with helical teeth. It is now of importance that the said guide bar 62 receives an absolutely 125

5 accurate adjustment, which exactly corresponds to the pitch of the respective teeth of the tool. For this purpose an arrangement is provided, which may be termed the micrometer adjusting attachment.

- The guide bar 62 is coupled by means of a bolt 71 (Fig. 10) with a sector 72 pivoted on a pin 63. This sector forms a part of a worm wheel and meshes with a worm 73. 10 The worm, to which a handwheel 74 is attached, is fitted freely revoluble on the one leg of an angle bolt 75 (shown separately below Fig. 6). The other end of the angle bolt engages in an arm 77 extending from 15 the bearing 76 of bar 62. On a collar 78 on bolt 75 is a mark (a cut) and on the collar 79 of the worm is a graduation from 0—9. To the end of bolt 75 is attached a pointer 80, the point of which plays over a 20 dial on sector 72. The zero of this dial coincides with the point of said pointer, when the guide bar 62 is absolutely horizontal, thus in an indifferent position, and there will be no twist of the mandril. The dial 25 is so divided that at each full revolution of the worm the sector will be moved by one graduation relatively to the pointer. The graduation on the collar of the worm allows the operator to set the attachment to 1/10 30 of a division of the dial on the sector. The guide bar 62 can be fixed in any adjusted position by means of nut 81 on bolt 63.

The mark on bolt 75 may also be omitted and the reading may be made along the 35 pointer.

The tool bears in the manner shown in Fig. 12 with the face of one of its teeth against the grinding wheel 13.

- According to the present invention a 40 chain weighted or under action of a spring is wound around the mandril spindle which is journalled freely revoluble in its bearings; the upper end of said spring being attached to a slide which may travel crosswise to the axis of said spindle and be fixed. The pull of the weight or spring has the effect that the spindle is held by friction with the chain in its operative (or grinding) position, providing that the grinding pressure 45 of the spindle acts in the direction of the pull of the weight or spring. If, however, the spindle is turned oppositely to the pull of said weight or spring, this may be performed without any nominal resistance, so 50 that such turning may be utilized for the advance of the tool or the accurate adjustment of the same. When the slide, to which the end of the chain is attached, is moved, the spindle will be turned, the hereinbefore 55 described conditions regarding the resistance against the turning of the spindle in the one direction, and the possibility of turning the spindle in the opposite direction remain. The rotation of the spindle produced 60 by means of the slide is utilized, when tools

with helical teeth are to be ground, with which the spindle must be turned corresponding to the twist of the helical teeth.

When tools have to be ground at a considerable pressure, the arrangements hereinbefore disclosed, and including those hereinbefore described will not or not very well be suited therefor. It is obvious that a correspondingly higher resistance can only be opposed to the higher grinding pressure by 70 the brake effect on the mandril spindle being increased. This may be obtained in the hereinbefore described arrangement by increasing the pull of the weight or the spring. By thus increasing the brake effect, however, 75 also the advance of the tool will become more difficult, so that it is either necessary to make provisions, to annul the brake effect during the advance, or to heavily weighten the advancing gear, for it to overcome the frictional resistance. In either instance the grinding will suffer thereby, by spring effects being introduced into the gearing, which will impair the production of straight 80 ground surfaces.

Whereas in the hereinbefore described arrangement the chain is wound once only around the spindle, the present invention provides for such purpose according to experience that the chain be wound several 90 times around the spindle. It is thereby secured that the spindle cannot by any means be turned in the direction of the pull of the chain, because the frictional resistance is too extraordinarily great, that it will resist even 100 the highest grinding pressure; but the spindle may without any essential resistance be turned in the opposite direction the same as before. It is thereby obtained that on the one hand the brake effect on the spindle 105 will meet very high grinding pressures, whilst on the other hand, the possibility of readily turning the spindle for advancing the tool is not reduced.

It is, in such case, important, that the individual turns of the chain do not touch each other, because, as soon as the spindle is turned from the slide, to which the end of the chain is secured, the chain will no more be stationary but be partially wound or unwound, respectively, whereby the thrums, if they rub against each other, would not only impare the effect but also be destroyed by wear. For preventing this the part of the chain which is to wind on the spindle is made 110 in such a manner that the links are set off one after the other to one side, whilst the free ends of the chain are straight. This arrangement is shown in Figs. 13-17.

On the body 8 of the machine the headstock 111 is disposed so as to be shiftable in longitudinal direction; to this headstock is attached a guide 56, in which a slide 55 travels crosswise to the axis of the spindle. This slide has at its lower end a block 80 which 115

glides between the guides 81 connected by set-screws, which may be set at will from the handwheel 74 by means of a worm gear, so that when the headstock 111 is shifted longitudinally, the slide 55 is moved transversely, when the guides 81 are set at an angle (contrary to the position shown in Fig. 13).

To the upper end of the slide 55 is attached the chain 64. This chain is wound in several 10 (3) turns around the spindle or a sleeve 29 connected to the spindle, said sleeve being freely revoluble in the bearings 26, 27 of the headstock. The other end of the chain is attached to a spring bolt 82, which is fitted 15 axially displaceable to the lower end of the slide 83 and is pulled downward by the spring 84 around it.

The spring 84 need be only quite weak, because the three turns of the chain on the 20 spindle will already afford so great a frictional resistance against the turning of the spindle in the one direction, that no considerable pull by weight or spring on the end of the chain is any more required. The 25 object is only to yieldingly secure the end of the chain, so as to keep the chain in order in its position.

As may be seen in particular from Fig. 17, the chain is so constructed, that its two ends 30 64¹ and 64² extend in a straight direction. The part of the chain, however, which winds on the sleeve 29 has its links set off to one side, so that the individual turns of the chain on the sleeve 29 will not touch each 35 other (Fig. 15). When the spindle is therefore turned, by the travel of the slide 55, the chain, winding onto or unwinding from the spindle, cannot rub with its turns against each other.

40 In the form shown in Fig. 16 the slide 55 is provided with a rack 85 in which engages a gear 86 loosely revoluble on sleeve 29. To this gear is secured the chain 64, constructed according to Fig. 15, and wound in several 45 turns around the sleeve 29, a mild pull being exerted on said chain by means of a spring 84 wound around the spring bolt 82.

Fig. 18 illustrates the bearing of the grinding wheel spindle of the machine in longitudinal section. The spindle is journaled in 50 two bearings 14; on the right would be the grinding wheel 13 to be secured by means of the screw thread 87.

The invention which is intended to be 55 chiefly employed with precision machine tools with high-speed spindle in thrust bearings, provides that the shaft revolves with two conical collars tapering towards each other, 88, 89 in two correspondingly bored 60 journals 90, 91. This type of bearing is employed for reason of the greater possibility of accurately adjusting the same.

If now, as it is the case in the left hand bearing with regard to cones 92, 93 and with 65 the right hand bearing with regard to the

cones 88, 89 the two cones of the bearing are fixed relatively to the shaft (on the left sleeve 94) an axial play will appear in the bearing on the latter being much heated, so that the spindle will greatly vibrate and the 70 accuracy of the work will suffer. In the bearing shown this trouble will be particularly noticed in the right hand bearing, because the latter is under the greater load, the 75 grinding wheel being fitted at 87, and because it also has to take up the whole axial thrust, as the extension 95 of the spindle 96 is axially shiftable in sleeve 94 by means of key 97, as may be seen in the drawing. For this reason the arrangement hereinafter described has been employed in the right hand bearing.

I may here point out that even if an even heating of the two cones 88, 89, on the one 80 one hand, and of the sleeve 90 on the other be supposed, the sleeve 90 must expand radially more when the sleeve is made in the usual and approved manner of gun metal, because the cones are made of steel or iron, when thus the metal of the sleeve has a 90 higher coefficient of expansion. The greater expansion causes the fit to slacken the more, because it produces a radial receding of the conical line of the sleeve 90 from the angle formed by the cones, thus a relative shortening 95 of the sleeve, which cannot be compensated by the greater longitudinal extension of the sleeve as a consequence of the higher coefficient of expansion.

For the purpose of maintaining the 100 original fit even when the bearings heat, the two cones 88, 89 will, therefore have to be approached towards each other in approximate correspondence with the increasing 105 heat or the expansion, respectively. According to the present invention the heat produced by the slipping of the belt is utilized in such a manner, that one of the cones, viz. 88, is formed by a sleeve 99 made in the form of a belt pulley 98. By said 110 sleeve 99, which drives the spindle 96 by means of a key 100, bearing against the abutment formed by the lock nuts 101, 102, it will, on being heated by the slip of the 115 belt, force the cone 89 to the right towards the cone 88 rigidly fitted to the spindle 96. As a heat producing agent not only the slip of the belt (which just at high speeds and small pulleys is unavoidably great) but also the lateral shifting of the belt (which likewise appears under the said conditions with a high number of oscillations). Besides the same as the heating of the bearing, also the heating of the sleeve 99 by the slip of the belt will increase with the duration of 120 the work and with the load, so that the utilization of the slip of the belt as source of heat for producing the expansion of a member shifting the one cone actually affords the means for counteracting the 125

slackening of the fit of the bearing caused by the heating of the latter.

The locknuts 101, 102 allow, as an adjustable abutment the regulation of the fit 5 of the bearing.

For adapting the grinding wheel to the twists of tools with helical teeth, the bearing 14 of the grinding wheel shaft is, as shown in Figs. 19 and 20, made in form 10 of a slide shiftable on the table 103. The grinding wheel is covered by a hood 104. The base of the bearing engages with a web in a groove 105 in the table 103 and may be fixed by a set screw 106. This 15 groove is curved to a circular line 107 the center of which is situated at α (see also arrow in Fig. 20), viz., in the vertical middle line of the grinding wheel 13. By shifting the sliding bearing the grinding 20 wheel 13 may be brought into any angular position, one of which is shown in Fig. 20. The intermediary position of the grinding wheel 13 shown in Fig. 19 is employed for tools with straight teeth.

25 With the new grinding machine both tools with pointed and with undercut teeth may be ground, it being immaterial whether their teeth are parallel to the axis of the tool or helically wound to the right or the 30 left, grinding wheels of any kind being used.

I claim:

1. In a tool grinding machine in which the tool is fitted on a mandrel held between 35 two center points fitted to a reciprocating slide, which moves the tool past a stationarily revolving grinding wheel, the combination of a freely revolvably journaled spindle carrying the one of said center 40 points, a flexible element wound around said spindle, a tensioning element connected to one end of said flexible element, the other end of said flexible element attached to a controlling member shiftable crosswise to 45 the axis of the said spindle.

2. In a tool grinding machine in which the tool is fitted on a mandrel held between 50 two center points fitted to a reciprocating slide, which moves the tool past a stationarily revolving grinding wheel, the combination of a freely revolvably journaled spindle carrying the one of said center 55 points, a flexible element wound around said spindle, a tensioning device connected to one end of the flexible element, the other end of said flexible element attached to a slide shiftable crosswise to the axis of the spindle, a pawl engaging in and arresting 60 said slide, an adjustable guide rail, and a roller on said slide, with which said slide rides on said adjustable guide rail, when not arrested by said pawl.

3. In a tool grinding machine in which the tool is fitted on a mandrel held between the 65 two center points fitted to a reciprocating

slide, which moves the tool past a stationarily revolving grinding wheel, the combination of a freely revolvably journaled spindle carrying the one of said center points, a flexible element loosely wound 70 around said spindle, a tensioning device connected to one end of said flexible element, the other end of flexible element attached to a slide shiftable crosswise to the axis of the spindle, a pawl engaging in and arresting 75 said slide, a guide rail adjustable on a pin and a roller on said slide, with which said slide rides on said adjustable swivelling rail, when not arrested by said pawl, said chain holding said slide down against said 80 guide rail, said guide rail fitted with a wormwheel sector, engaging with a worm having a handwheel, and a pointer and dial for reading the relative adjustment of said worm and sector.

4. In a tool grinding machine in which the tool is fitted on a mandrel held between two center points fitted to a reciprocating slide, which moves the tool past a stationarily revolving grinding wheel, the combination of a freely revolvably journaled spindle carrying the one of said center points, a flexible element consisting by one half of two parallel thrums, in the other half of one central thrum adapted to engage in the gap 90 between the other two thrums, said chain wound with its two-thrum part loosely 95 around said spindle, the one-thrum end of said chain carrying a flexible element, the other two-thrum end attached to a slide shiftable crosswise to the axis of the spindle a pawl engaging in and arresting said slide, a guide rail swivellingly adjustable on a pin and a roller on said slide, with which said slide rides on said adjustable swivelling 100 guide rail, when not arrested by said pawl, said chain holding said slide down against said guide rail, said guide rail fitted with a worm-wheel sector, engaging with a worm 105 having a handwheel, and a pointer and dial for reading the relative adjustment of said worm and sector.

5. In a tool grinding machine in which the tool is fitted on a mandrel held between two center points fitted to a reciprocating 115 slide, which moves the tool past a stationarily revolving grinding wheel, the combination of a freely revolvably journaled spindle carrying the one of said center points, a flexible element, wound around the said spindle, the one end of said element carrying a tensioning device, the other end of said element attached to a controlling member shiftable crosswise to the axis of the said spindle, a ratchet wheel having the same number of 120 teeth as the tool to be ground fitted on the spindle holding the mandrel, a pawl engaging in said ratchet wheel and carried by a member, revolvable on the mandrel spindle, means for oscillating said member on the 125 130

completion of the reciprocating operative stroke of the mandril, on said pawl an extension, a controlling member held by friction in the mandril spindle bearing and having a recess, in which said pawl extension engages.

6. In a tool grinding machine in which the tool is fitted on a mandril held between two center points fitted to a reciprocating slide, 10 which moves the tool past a stationarily revolving grinding wheel, the combination of a freely revolubly journalled spindle carrying the one of said center points, means acting on said spindle and adapted to turn said 15 spindle in one direction, to hold said spindle in a given position (grinding position) and to allow of the said spindle being turned in the opposite direction on a force exceeding the grinding pressure acting on the said 20 spindle, a slide carrying the grinding wheel, said slide having a web or the like, in the slide table a groove of a circular curve, the center of said circular curve being in the vertical middle line of the grinding wheel, 25 said web engaging in said groove.

7. In a tool grinding machine in which the tool is fitted on a mandril held between two center points fitted to a reciprocating slide, which moves the tool past a stationarily revolving grinding wheel the combination of a freely revolubly journalled spindle carrying the one of said center points, means acting on said spindle, adapted to turn said spindle in one direction, to hold the said spindle in 30 a given position (grinding position) and to allow of the said spindle being turned in the opposite direction on a force exceeding the grinding pressure acting on the said spindle, the grinding wheel spindle having a double 35 conical bearing, the one of the cones formed by a sleeve non-revolubly fitted to the spindle, and bearing against an abutment on said spindle, said sleeve so formed as to simultaneously serve as belt pulley.

8. In a tool grinding machine in which the tool is fitted on a mandril held between two center points fitted to a reciprocating slide, which moves the tool past a stationarily revolving grinding wheel, the combination of 40 a freely revolubly journalled spindle carrying the one of said center points, means acting on said spindle, adapted to turn said spindle in one direction, to hold the said spindle in a given position (grinding position) and to allow of the said spindle being turned in the opposite direction on a force 45 exceeding the grinding pressure acting on the said spindle, the grinding wheel spindle having a double conical bearing, the one of the cones formed by a sleeve non-revolubly fitted to the spindle, and bearing against an abutment on said spindle, consisting of two 50 adjustable lock-nuts, said sleeve formed to simultaneously serve as belt pulley.

9. In a tool grinding machine in which the tool is fitted on a mandril held between two center points fitted to a reciprocating slide, which moves the tool past a stationarily revolving grinding wheel, the combination of a freely revolubly journalled spindle carrying the one of said center points, a chain wound several turns around said spindle, in the part of the said chain which is thus wound around said spindle the links continuously set off on one side, 70 the one end of said chain carrying a tensioning device, the other end of said chain attached to a controlling member shiftable crosswise to the axis of the said spindle. 75

10. In a tool grinding machine in which the tool is fitted on a mandrel held between two center points fitted to a reciprocating slide, which moves the tool past a stationarily revolving grinding wheel, the combination of a freely revolubly journalled spindle carrying the one of said center points, a chain wound several turns around said spindle, in the part of the said chain which is thus wound around said spindle the links continuously set off on one side, the one end of said chain carrying a tensioning device, the other end of said chain attached to a slide shiftable crosswise to the axis of the spindle, a block on said slide, two guides adapted to be obliquely adjusted, said block 90 on said slide, sliding between said adjustable guides. 95

11. In a tool grinding machine, a cutter shaft adapted to carry a cutter, a tool supporting spindle adapted to carry a tool, 100 means for intermittently advancing said spindle in strokes of predetermined length, and adjusting means for causing the lead and lag of said strokes dependent upon the relative wear and adjustment of said cutter 105 and tool for maintaining desired pressure between the same.

12. In a tool grinding machine, a cutter shaft adapted to carry a cutter, a tool supporting spindle adapted to carry a tool, a 110 reciprocating member for advancing said spindle in strokes of predetermined length, and variable adjusting means arranged between the reciprocating member and the spindle for causing the lead and lag of said 115 tool and cutter.

13. In a tool grinding machine, a cutter shaft adapted to carry a cutter, a tool supporting spindle adapted to carry a tool, a reciprocating member for advancing the 120 spindle in strokes of predetermined length, a differential mechanism connected between said reciprocating member and said spindle, and means for adjustably anchoring an element of said differential mechanism for 125 causing advance of said spindle, said means when adjusted being adapted to vary the lead and lag of said stroke through said dif-

ferential mechanism whereby to maintain desired pressure between said cutter and tool.

14. In a tool grinding machine, a cutter shaft adapted to carry a cutter, a tool supporting spindle adapted to carry a tool, a differential mechanism connected to said spindle, a reciprocating member connected to said differential mechanism for actuating the same in strokes of predetermined length, and a manually adjustable device connected to the differential mechanism for anchoring the intermediate element thereof to effect

advancement of said spindle through said differential mechanism upon operation of 15 said reciprocating member, said manually adjustable device being adapted to vary the lead and lag of said strokes whereby to maintain a predetermined relation between said cutter and tool. 20

In testimony whereof I affix my signature in presence of two witnesses.

FRANZ-LOUIS WÄCHTLER.
